DIAPER HAMPER WITH DEODORIZING MEANS

Arthur J. Zucker and Bernard Heiblim, Passaic, N. J., assignors, by direct and mesne assignments, to Hamper-Tainer Co. Inc., Passaic, N. J., a corporation of New Jersey

Application September 8, 1953, Serial No. 378,825

3 Claims. (Cl. 229—14)

The present invention relates to certain new and useful improvements in containers, generally speaking, and has more particular reference to one which may be conveniently identified as a hamper for soiled diapers, for example, a hamper which is such in construction and purpose that the requirements of the manufacturer, the diaper laundering and supply concern, and the needs of everyday users will be satisfactorily met.

In carrying out the principles of the invention, the usual conventional-type diaper container will be eliminated and the herein described temporary cardboard or equivalent container or hamper will be substituted therefor in order to dispense with the idea of using a permanent metal container over and over by different customers and whereby to permit the use of the temporary container using one for each customer and requiring no reserving in that when the particular customer is through with it, it is then, because of its economical character, demolished and disposed of.

Another advantage insofar as the diaper service concerns and operators are concerned is derived from the fact that the hamper is such in construction that it is manufactured for assembling in knock-down form, that is, in a form in which the principal walls or parts are flat and are shipped flat in cartons and are such in construction that they are then assembled and stapled together by the diaper service operators and consequently readily brought into use in order that a new one may be supplied to each new customer.

Another object of the invention has to do with the provision of a container which is durable, light and easy to handle, decorative, and by test completely practical, is completely water-proof, satisfactorily confines objectionable odors, and because of the price factor each customer gets a new container whereas previously metal containers were shifted from one home to another after completion of use, there being no need therefore, to cope with objectionable rust and corrosion.

Briefly summarized, the invention therefore has to do with a temporary-type hamper or container as a substitute for a permanent metal type which is constructed from cardboard or equivalent economical throwaway stock, said container being adapted to be furnished new to each new customer and then demolished and disposed of after its turn of service has expired, said container embodying an open-top receptacle having a moisture-proofing liner of non-absorbent material, and a readily attachable and detachable cover, said cover having a perforated box on its interior containing a deodorant.

Then, too, novelty is predicated on the above adaptation wherein the components of said container, including said cover, are manufactured in flat sheet form and compactly packaged and shipped in knockdown ready-to-use condition, this to conserve space and to likewise expedite the step of assembling by the diaper supply company, and furnishing the completed container for use by each new customer.

Other objects, features, and advantages will become

2

more readily apparent from the following description and the accompanying sheet of illustrative drawings.

In the drawings, wherein like numerals are employed to designate like parts throughout the views:

Figure 1 is a perspective view with a portion broken away to show details of construction;

Figure 2 is a fragmentary section on an enlarged scale taken approximately on the line 2—2 of Figure 1 looking in the direction of the arrows;

Figure 3 is a top plan view of the blank from which the principal part of the cover is constructed;

Figure 4 is a perspective view of the especially constructed insert or lining for the cover;

Figure 5 is likewise a perspective view illustrating the particulars of construction; and

Figure 6 is section taken on an enlarged scale on the irregular line 6—6 of Figure 4 looking in the direction of the arrows.

Referring now to the drawings by reference numerals, 20 the body is denoted by the numeral 8, and it is made of specially prepared corrugated cardboard durable, waterproofed, and covered with a plastic coating. It is made flat and folds and rolls into an octagonal-shaped cylinder made possible by dye cut tongues at top and bottom portions of the body. In the drawings, the originally flat sheet of cardboard is shown formed into an open-ended tubular body or cylinder. The circumferentially spaced tongues at the top are bent inwardly and downwardly as at 10. Similarly the dye cut tongues at the bottom are 25 bent inwardly on the fold line 12 and then upwardly as denoted at 14. The cooperating elevated cardboard bottom 16 has laterally and downwardly bent tongues 18 which overlap and are bent on the fold lines 20 and which interlock with the tongues 14, the respective tongues 14 and 18 being stapled together as at 22. The numeral 24 denotes a polyethylene bag which constitutes a lining for the closed-bottom container. This lining is completely waterproof and non-absorbent and is placed in the interior of the body after the dye cut locks or tongues are 30 folded into the body as at 10. It might be stated in this connection that the upper open end of the bag is folded upon itself as at 26, and it is stapled and thus held in place as at 28. Thus stapled with galvanized staples, the bag becomes the permanent lining which waterproofs 35 and odorproofs the container interiorly. This procedure also adds to the desired rigidity at the top of the container, as is obvious. Incidentally, the numeral 30 designates a canvas or equivalent bag containing diapers which is located within the lined container or hamper.

40 Taking up now the component which is here referred to as the cover, this is denoted generally by the numeral 32 and it also is of cardboard. That is to say, it is made flat and of the same material as the body and bottom. The cover has a flat, central, octagonal portion 34 and the marginal edges are dye cut to provide shaping and reinforcing rim means. That is to say, the construction described provides a down-bent rim which is adapted to telescopically embrace the upper portion of the container in the manner best shown in Figure 2. More specifically, 45 there are marginal circumferentially spaced dye cut flange complements 36 which are of tongue-like form and these are individually bent on the fold lines 38 and then again bent or doubled on the fold lines 40 to provide the tucked-in double thickness illustrated in Figures 1 and 2, the substantially rectangular portions thereof being denoted at 42 and 44, respectively, and with the portions 44 wherever necessary or desired with or without the extension and connecting tabs 46. These tabs overlap adjacent flange portions and the respective portions are 50 stapled together as at 48. A handle 50 is provided and this is handily riveted or otherwise fastened in place as at 52. More importantly, the cover includes what con-

55 60 65 70 75 80 85 90 95

stitutes a novel insert or liner. This is best shown in Figures 4, 5, and 6. The liner is held in place by the stapled flange-complements 36 as best shown in section in Figure 2. This liner is of cardboard, and comprises a pair of duplicate half-sections 54 and 56 each of semi-octagonal form with adjacent marginal edge portions 58 and 60 spaced apart as shown in Figure 5. The patterns forming these complementary portions are so stamped or cut out along the edge portions 58 and 60 as to simultaneously define the components or parts of a perforated deodorant containing box or holder. That is to say, the main body portion of the box is denoted at 62 and this has transverse end portions 64—64 foldably integrated with the edge portions 58 and 60 of the two half-sections 54 and 56. In addition, there are individual folding flanges 66 and 68 along the longitudinal sides which have extension or retaining tabs 70—70. By reference to Figure 5 and assuming that the two sections 54 and 56 are pressed together in coplanar relationship and the flanges 66 and 68 are properly bent in suitable angular relationship, the tabs 70—70 are tucked into the then abutting edge portions 58 and 60 to thus cooperate and define the perforated box-like holder as illustrated in Figures 4 and 6 in particular. The manner of stamping out the cover liner and the way in which the half sections are brought together in coplanar relation to thus fold the complements of the box into box-forming relationship, is believed to be highly novel.

Reverting now to the handle 50, the fasteners 52 are more specifically in the form of bolts. In actual practice, when the half-sections 54 and 56 are brought together the edges 58 and 60 approaching each other serve to transform the scored web into a deodorant box as is evident. The bolt holes 51 therein are lined up with bolt holes in the cover portion 34. Then, when the bolts pass through the aligned bolt holes the liner is bolted to the cover and the handle is simultaneously fastened in place. This then makes it easy and possible to axially superimpose the liner on the cover and to bolt it in place and thereafter to fold and bend the flange components in such a way that the inwardly directed rectangular portions have their edges spaced from the body portion 34 leaving a sort of a space or channel all the way around and into which the marginal edge portions of the half sections 56 are fitted and "keyed" in place and securely held in the manner seen in Fig. 2.

Novelty is predicated on the temporary economical cardboard aspects of the over-all hamper, the parts from which the hamper is assembled and made up for use, especially as specifically herein shown and described and on the over-all finished hamper or container, that is including the readily applicable and removable cover with the special liner appearing in Figures 4 and 5.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A diaper hamper of the class described comprising

a container open at its top and closed at its bottom, a readily applicable and removable handle-equipped cover, said cover having a marginal flange and said flange being made up of circumferentially spaced independently bent flange complements, said flange complements being made up of components folded upon themselves and providing a double thickness construction, and certain of said complements having extending tabs and said tabs being interlocked with other complements and stapled to provide a substantial rim for said cover, and a liner for the bottom side of said cover, said liner comprising companion coplanar half-sections having abutting edge portions joined together by a connecting web, and said web being apertured and being fashioned into and serving as a deodorant holding box.

2. For use on a diaper hamper, a cover having a flat faced body portion and a laterally disposed endless marginal rim, a sheet material insert comprising a liner for said cover and applied against and contacting the bottom side of said bottom portion and having peripheral edge portions confined by and physically held in place by cooperating portions of said rim, said insert embodying a pair of complementary coplanar half-sections having inner adjacent edge portions abutting each other, and a web having foldable end portions integral with intermediate portions of the abutting edge portions of the half-sections, said web proper being disposed in spaced parallelism and in a plane below the bottom side of the abutting half-sections and being provided with wall forming flanges which in conjunction with the web and cooperating half-sections provide a deodorant containing box.

3. For use on a diaper hamper, a cover having a body portion and marginal laterally directed rim; a liner for said cover adapted to be superimposed against the bottom side of said body portion, said liner being struck out from manually foldable sheet material and embodying a pair of substantially duplicate coplanar half-sections which are flat and have adjacent edge portions which are adapted to abut each other, intermediate portions of said edge portions being interconnected by way of a web, said web having cooperating foldable portions which are integrally joined to each other and the edge portions of the respective half-sections and being further provided with tongue-equipped side flanges, said side flanges being foldable in conjunction with the foldable portions of the web and functioning, in conjunction with said half-sections to provide a deodorant containing box.
